UNITED STATES PATENT OFFICE.

LEONID A. DUNAJEFF, OF NEW YORK, N. Y.

LIQUID-FEEDING DEVICE.

Application filed July 18, 1921, Serial No. 485,659. Renewed June 19, 1923.

To all whom it may concern:

Be it known that I, LEONID A. DUNAJEFF, citizen of the United States, and resident of New York, in the county of New York and 5 State of New York, have invented certain new and useful Improvement in Liquid-Feeding Devices, of which the following is a specification.

My invention relates to liquid feeding devices and has a particular reference to the apparatus adapted for transferring liquids from spaces of a lower pressure into spaces of a higher pressure.

The ordinary method for such transfer 15 of liquids,—for instance, in feeding the water into a boiler,—the work of moving the water into the boiler against the steam pressure requires a considerable expenditure of energy, also more or less complicated mechanical pumps.

In my apparatus I am using a different method. Instead of forcing the water against the steam pressure, I let the water flow into the boiler by gravity from an enclosed tank, the pressure in which is equalized with the boiler pressure. Consequen- 25 tly each volume of water entering the boiler is replaced with a corresponding volume of the steam, so that the steam consumption can 30 not exceed the volumetric equivalent of the water fed into the boiler, which is only about one sixth of the theoretical steam consump- 35 tion of an ordinary boiler feed pump.

The operation of my device consists of two 40 stages: First, the connections with the boiler are closed, and the apparatus is filled with the water. Then the water connections are closed, and connections with the boiler are opened, allowing the water to flow into the boiler by gravity, the water in my apparatus being displaced with the steam from the 45 boiler.

My invention is more fully described in the accompanying specification and drawings, in which—

Fig. 1 is a sectional elevation, Fig. 2 is a 50 sectional view of the slide valve, and Fig. 3 is a view showing arrangement of two apparatus, one for draining condensate and another for feeding the boiler.

My device consists of a tank 1 and a liquid storage tank or well 2 located preferably above the tank 1, so that the liquid may flow by gravity between these tanks. The 55 lower portion of the tank 1 is connected with the lower portion of the well 2 with an in-

take pipe 3. A valve 4 is placed in this pipe in such manner, that the pressure of the liquid from the pipe 3 tends to raise this valve, while a pressure from the tank 1 tends to close it. The storage tank 2 is insulated from the tank 1 with a double bottom, consisting of plates 4 and 5 with a heat insulating material 6 between them. Such insulation is useful when the apparatus 60 is used for feeding water into a boiler 7 or similar receptacle, so that the cold water in the tank 2 would not absorb the heat from the steam in the upper portion of the tank 1. An air ram 8 with a plug 9 is mounted 65 on top of the tank 2 to provide the space for the air, which may escape from the water.

The tank 2 is refilled with the water 70 through leading-in pipe 10 with a sprayer tube 11. This pipe may bring the water from any suitable source, for instance, from the water mains or from condensers.

The water from the tank 1 flows into the 75 boiler 7 through a feed pipe 12 connected to the bottom of the tank 1 with an elbow 13, and reaching to the bottom of the boiler 7. A valve 14 is placed in this elbow so that the pressure of the flowing water tends to open it, while the boiler pressure closes it. 80

The upper portion of the tank 1 is connected with a slide valve 15 through a tubular passage 16. The valve 15 controls the connections of the upper portion of the tank with the air space (or vacuum) in the well 2 through a pipe 17 and with the steam in the boiler through a pipe 18. 85

The slide valve consists of a piston 19 in a cylinder 20. The piston has a central circular groove 21 which in the extreme upper position of the piston establishes a communication between the pipes 16 and 17, and in the lowest position between the pipes 16 and 18. The bottom portion of the piston is connected loosely with a rod 22 supporting a steam intake valve 23 and a steam exhaust valve 24. The steam admittance under the piston 19 is further controlled by the position of the water valve 14. 90

This valve has a hollow stem 25 with an opening 26 on the side. The stem slides in a cylinder 27 with a corresponding opening 28 in a communication with a pipe 29 connected with a steam pipe 18. 105

When the valve 14 is in its open or raised position, then the holes 28 and 26 come in an alignment, so that the steam can flow from 110

the pipe 29 into a chest 30, through a pipe 31 and the valve 23. If the valve 23 is open, then the steam fills the chest 30, pushing the piston 19 upwards. In order to prevent a very rapid movement of this piston, a dampening attachment is provided. It consists of a diaphragm 32 with a small aperture 33 on the side and a larger aperture 34 in the center for a rod 35 attached to the top of the piston 19. The upper end of this rod is fastened to a damper piston 36 having a cup shaped depression 37 on top and supporting a compression spring 38. The other end of the spring rests against an adjusting nut 39. The spaces 40 and 41 above and below the diaphragm 32 are filled with the oil, which fills also the cup 37. The reciprocating movements of the piston force the oil through the passage 33. The smaller the passage is, the slower will be the movement of the piston. In order to adjust its speed, the size of the opening 33 may be regulated by means of an adjusting screw or needle valve 42.

25 The oil in chambers 40 and 41 will serve also as a lubricant for the moving parts. In order to keep these compartments full at all times, a provision is made to refill them constantly from the cup 37. A hole 43 is drilled 30 for this purpose through this piston and is closed from the bottom with a valve 44 with a long stem 45, passing with a slight friction through the diaphragm 32. This friction will cause the valve 43 to be closed when 35 the piston moves downwards so as to prevent the escape of the oil from the chamber 39 into the cup 37, and will open this valve with the upward movement of the piston so as to suck in the oil from the cup.

40 The supply of oil in the cup may be replenished from time to time through an aperture 45 in the closing nut 38. A screw 53 may be used to regulate the friction of the rod 45 (Fig. 2).

45 The operation of my device is as follows: The water is first admitted into the well 2 through the pipe 10. Then, if the piston 19 is in its highest position, the steam or air is allowed to escape from the upper portion 50 of the tank 1 through pipes 16 and 17, and the water from the well 2 flows into the tank 1, forcing the valve 4 open, until the tank becomes filled. The piston 19, however, when in its upper position, closes the steam 55 intake valve 23 and opens the exhaust 24, allowing the steam to escape from the chamber 30 through the pipe 17. Accordingly the piston will begin to move downwards, partly by its weight, partly under the action 60 of the spring 39.

The dampening attachment will retard this movement sufficiently until the tank becomes filled with the water.

65 The piston 19 in its lowest position forces the rod 22 down, thereby opening the steam

intake valve 23 and closing the exhaust 24. The steam can not enter the compartment 30, however, as long as the steam pressure keeps the water valve 14 down, thereby disconnecting the passages 26 and 28.

70

With the valve 19 in its lowest position (Fig. 2) the pipe 17 becomes disconnected from the tank 1, and the steam from the boiler is admitted through the pipe 18, filling the space in tank above the water.

75

The pressure on the water in the tank will be equalized between the pipes 18 and 12, so that the weight of the water will raise the water intake valve 14, and the water will flow into the boiler, its place in the tank being taken by the steam from the pipe 18. The steam pressure at the same time will close the water intake valve 4.

80

The steam will now flow from the pipe 29 through passages 26, 28, hollow stem of the valve 14, pipe 31, through the steam valve 23 to the chest 30, and will push the piston 19 upwards. Its movement will be slow, however, on account of a retarding action of the oil damper. By the time, when the piston reaches its upper position, all the water will be discharged into the boiler, and the valve 14 will close the pipe 13, disconnecting also the steam flow between the passages 26 and 28.

95

With the piston 19 in its upper position the steam will be cut off from the tank 1 and, instead, a connection will be established with the exhaust pipe 17, allowing the steam to escape from the tank 1 into the well 2, where it will be condensed by the action of the spray of the water from the sprayer 11. The water will then flow into the tank 1 through the valve 4, the other operations taking their turn over again as described.

100

The condensing steam in the well 2 will create a vacuum, so that the water may be raised to this apparatus from the lower level through a vertical distance of some 10 to 15 feet.

110

When the water has to be raised to a greater height, then another apparatus must be installed at the lowest point. Fig. 3 shows an arrangement with two such apparatuses. The upper apparatus I feeds the water from the tank 1 into the boiler 7 underneath. The lower apparatus II receives its water from a condenser 46 through the water pipe 3'. The pressure is equalized by means of a vacuum pipe 17'. The water from the tank 1' flows through a pipe 12' into the tank 1 of the apparatus I. The water is forced against the gravity in this case by the steam pressure, the steam being admitted into the tank 1' through the pipe 18' and the valve 52 from the boiler 7.

115

Instead of using steam from the boiler for the tank 1', the exhaust steam from the tank 1 may be utilized. For this purpose the exhaust steam from the tank 1 is di-

120

125

130

rected through the pipe 17, check valve 48 and a valve 51 into a steam receiver 55. This receiver is connected by means of a pipe 47 with the pipe 18' and apparatus 511. The valve 52 is closed, when steam from the receiver 55 is used.

The end of the pipe 18 is placed at the point of the normal water level in the boiler. Therefore, when the boiler is full, the water 10 instead of steam will be drawn into the pipe 18 by the suction of the water flowing from the tank 1. But as soon as the height of the water in the pipe 18 reaches the water level in the tank 1, the water columns will 15 become balanced, and the flow of the water into the boiler will thereby automatically stop, and the apparatus will cease to function until the water level in the boiler will drop below the end of the pipe 18.

20 In order to insure the proper seating of the valves 23 and 24 and to prevent their chattering, they are provided with springs 49 and 50.

A float 54 of some heat insulating material (for instance, cork) is placed in the tank 1 in order to separate the water from the steam and thereby to prevent the excessive steam condensation when the cold water is used.

30 An important advantage of my apparatus is, that it is very economical in operation, using less steam than any ordinary pump. For each unit of the water volume placed into the boiler there is a corresponding volume of steam removed. For instance, for 62 lbs. of water pumped (one cubic foot) only about 2 lbs. of steam (one cubic foot) will be used, and the largest part of it will be condensed and pumped 35 back, preheating the feed water.

40 Other advantages of my device are, that it can pump a hot water, almost boiling, is automatic in its operation, very simple in construction, not having any moving parts except valves. It may be used for boiler feed, for condensate removal, for pumping 45 various liquids from one place into another, etc.

I claim as my invention:

50 1. In a liquid feeding device, the combination with a tank, a pipe connecting said tank with a source of a liquid, an intake valve on said pipe, a pipe connecting the lower portion of said tank with a receptacle for said liquid, an exhaust valve on said pipe, an exhaust pipe for the elastic fluid inside of said tank, an intake pipe for the compressed elastic fluid, and a means to control the connection of said pipes for said elastic fluid, said means being controlled by said exhaust valve.

55 2. In a liquid feeding device, the combination with a tank, a pipe connecting said tank with a source of a liquid, an intake valve on said pipe, a pipe connecting the

lower portion of said tank with a receptacle for said liquid, an exhaust valve on said pipe, an exhaust pipe for the elastic fluid inside of said tank, an intake pipe for the compressed elastic fluid, and a sliding valve adapted to control the connections of said intake and exhaust pipes, said sliding valve being controlled by said exhaust valve.

3. In a liquid feeding device, the combination with a tank, a pipe connecting said tank with a source of a liquid, an intake valve on said pipe, a pipe connecting the lower portion of said tank with a receptacle for said liquid, an exhaust valve on said pipe, an exhaust pipe for the elastic fluid, an intake pipe for the compressed elastic fluid, and a sliding valve adapted to control the connections of said intake and exhaust pipes, said sliding valve being operated by said compressed fluid and controlled by said exhaust valve.

4. In a liquid feeding device, the combination with a tank, a pipe connecting said tank with a source of a liquid, an intake valve on said pipe, a pipe connecting the lower portion of said tank with a receptacle for said liquid, an exhaust valve on said pipe, an exhaust pipe for the elastic fluid, an intake pipe for the compressed elastic fluid, a sliding valve adapted to control the connections of said intake and exhaust pipes, and means to dampen the movements of said sliding valve.

5. In a liquid feeding device, the combination with a tank, a pipe connecting said tank with a liquid containing well, an intake valve on said pipe, a liquid exhaust pipe connecting the lower portion of said tank with a receptacle for said liquid, an exhaust valve on said exhaust pipe, an exhaust pipe for the elastic fluid connecting the upper portion of said tank with the upper portion of said well, an intake pipe for the compressed elastic fluid connecting said tank with a receptacle for the liquid and for said compressed elastic fluid, a sliding valve controlling the connections with the tank of said elastic fluid intake and exhaust pipes, and means to admit the elastic fluid to the end of said sliding valve, said means being controlled by the movements of said sliding valve.

6. In a liquid feeding device, the combination with a tank, a liquid intake pipe, a liquid exhaust pipe, an elastic fluid intake pipe, an elastic fluid exhaust pipe, a sliding valve controlling connections of said elastic fluid pipes, said sliding valve consisting of a cylinder, a piston in said cylinder, a spring in one end of said cylinder, acting against said piston, a compartment in another end of said cylinder, and means to control the admittance of the elastic fluid to said compartment.

7. In a liquid device, the combination

- with a tank, a liquid intake pipe, a liquid exhaust pipe, an elastic fluid intake pipe, an elastic fluid exhaust pipe, a sliding valve controlling connections of said elastic fluid pipes, said sliding valve consisting of a cylinder, a piston in said cylinder, a spring in one end of said cylinder, acting against said piston, a compartment in another end of said cylinder, and valves in said compartment for the elastic fluid.
8. In a liquid feeding device, the combination with a tank, a liquid intake pipe, a liquid exhaust pipe, an elastic fluid intake pipe, an elastic fluid exhaust pipe, a sliding valve controlling connections of said elastic fluid pipes, said sliding valve consisting of a cylinder, a piston in said cylinder, a spring in one end of said cylinder acting against said piston, a compartment in another end of said cylinder, and intake and exhaust valves in said compartment for the elastic fluid, said valves being operated by said piston.
9. In a liquid feeding device, the combination with a tank, a liquid intake pipe, a liquid exhaust pipe, an elastic fluid intake pipe, an elastic fluid exhaust pipe, a sliding valve controlling connections of said elastic fluid pipes, said sliding valve consisting of a cylinder, a piston in said cylinder, a spring in one end of said cylinder acting against said piston, a compartment in another end of said cylinder, means to control the admittance of the elastic fluid to said compartment, and a damper for said cylinder.
10. In a liquid feeding device, the combination with a tank, a liquid intake pipe, a liquid exhaust pipe, an elastic fluid intake pipe, an elastic fluid exhaust pipe, a sliding valve controlling connections of said elastic fluid pipes, said sliding valve consisting of a cylinder, a piston in said cylinder, a spring in one end of said cylinder acting against said piston, a compartment in another end of said cylinder, means to control the admittance of the elastic fluid to said compartment, and a damper for said cylinder.
- 40 a sliding valve controlling connections of said elastic fluid pipes, said sliding valve consisting of a cylinder, a piston in said cylinder, a spring in one end of said cylinder acting against said piston, a compartment in another end of said cylinder, means to control the admittance of the elastic fluid to said compartment, and a damper for said cylinder, said damper consisting of a damper piston, a rod connecting said damper piston with said valve piston, and a stationary diaphragm between said pistons.
- 45 55 60 65 70 75 80 85 90 95 100 105 110 115 120 125 130
11. In a liquid feeding device, the combination with a tank, a liquid intake pipe, a liquid exhaust pipe, an elastic fluid intake pipe, an elastic fluid exhaust pipe, a sliding valve controlling connections of said elastic fluid pipes, said sliding valve consisting of a cylinder, a piston in said cylinder, a spring in one end of said cylinder, acting against said piston, a compartment in another end of said cylinder, means to control the admittance of the elastic fluid to said compartment, and a damper for said cylinder, said damper consisting of a damper piston, a rod connecting

said damper piston with said valve piston, a stationary diaphragm between said pistons, an aperture in said diaphragm, and means to control the size of said aperture.

12. In a liquid feeding device, the combination with a tank, a liquid intake pipe, a liquid exhaust pipe, an elastic fluid intake pipe, an elastic fluid exhaust pipe, a sliding valve controlling connections of said elastic fluid pipes, said sliding valve consisting of a cylinder, a piston in said cylinder, a spring in one end of said cylinder, acting against said piston, a compartment in another end of said cylinder, means to control the admittance of the elastic fluid to said compartment, and a damper for said cylinder, said damper consisting of a damper piston, a rod connecting said damper piston with said valve piston, a stationary diaphragm between said pistons, an aperture in said diaphragm, means to control the size of said aperture, a dampening liquid between said pistons, and a valve in said damper piston.

13. In a liquid feeding device, the combination with a tank, a pipe connecting said tank with a source of a liquid, an intake valve on said pipe, a pipe connecting the lower portion of said tank with a receptacle for said liquid, an exhaust valve on said second pipe, said valves being operated by the pressure of said liquid, and means to admit an elastic fluid under compression into said tank, said means consisting of a valve adapted to be operated by said elastic fluid, the admittance of said elastic fluid to said valve being controlled by said liquid exhaust valve.

14. In a liquid feeding device, the combination with a tank, means to fill said tank with a liquid, means to transfer said liquid into a receptacle by replacing said liquid with an equal volume of an elastic fluid under compression, and a float in said tank made of a heat insulating material.

15. In a liquid feeding device, the combination with a tank, a pipe connecting said tank with a source of a liquid, an intake valve on said pipe, a pipe connecting the lower portion of said tank with a receptacle for said liquid, an exhaust valve on said second pipe, a pipe connecting the upper portion of said tank with a source of elastic fluid under compression, a valve on said pipe controlling the flow of said elastic fluid and being operated by said elastic fluid, an auxiliary valve controlling the flow of said elastic fluid to said elastic fluid valve, said auxiliary valve being operated by one of said valves for the liquid.

16. In a liquid feeding device, the combination with a tank, a pipe connecting said tank with a source of a liquid, an intake valve on said pipe, a second pipe connecting said tank with a receptacle for said liquid, an exhaust valve on said second pipe, a pipe

- connecting said tank with a source of an elastic fluid under compression, a second pipe for elastic fluid connecting said tank with a space of a low pressure, a valve controlling the flow of said elastic fluid through said pipes, said valve being operated by an elastic fluid, and means to control the flow of said elastic fluid for the operation of said valve, said means being operated by one of 5
10 said liquid valves.
17. In a liquid feeding device, the combination with a tank, a pipe connecting said tank with a source of a liquid, an intake valve on said pipe, a second pipe connecting said tank with a receptacle for said liquid, an exhaust valve on said second pipe, a pipe connecting said tank with a source of an elastic fluid under compression, a second pipe for elastic fluid connecting said tank 15
20 with a space of a low pressure, and a valve adapted to control the connection of said pipes for the elastic fluid, said valve being operated by said elastic fluid and controlled by one of said liquid valves.
18. In a liquid feeding device, the combination with a tank, a pipe connecting said tank with a source of a liquid, an intake valve on said pipe, a second pipe connecting said tank with a receptacle for said liquid, an exhaust valve on said second pipe, a pipe connecting said tank with a source of an elastic fluid under compression, a second pipe for 25
30
- the elastic fluid connecting said tank with a space of a low pressure, a valve adapted to control the connections for said elastic fluid, 35 means to continuously apply a force on said valve in one direction, and means to intermittently move said valve in the opposite direction, said last named means being controlled by one of said valves for said liquid 40 through action of said elastic fluid.
19. In a liquid feeding device, the combination with a tank, a pipe connecting said tank with a source of a liquid, an intake valve on said pipe, a second pipe connecting said tank with a receptacle for said liquid, an exhaust valve on said pipe, a pipe connecting said tank with a source of an elastic fluid under compression, an exhaust pipe for said elastic fluid, a valve controlling 45
50 the connections of said pipes for said elastic fluid, means to apply a force on said valve continuously in one direction, means to operate said elastic fluid valve intermittently in the other direction by means of said 55 elastic fluid, said last named means being controlled by one of said liquid valves and means to regulate the flow of said liquid into said receptacle so as to maintain a constant level of said liquid in said receptacle. 60

Signed at New York in the county of New York and State of New York this 7th day of July A. D. 1921.

LEONID A. DUNAJEFF.
